UNITED STATES PATENT OFFICE.

CARL T. E. ZIMMERMAN, OF CUMBERLAND, WISCONSIN.

PENDULUM-ESCAPEMENT.

SPECIFICATION forming part of Letters Patent No. 633,938, dated September 26, 1899.

Application filed April 5, 1899. Serial No. 711,822. (No model.)

To all whom it may concern:

Be it known that I, CARL T. E. ZIMMERMAN, of Cumberland, in the county of Barron and State of Wisconsin, have invented a new and 5 useful Improvement in Clock-Escapements, of which the following is a specification.

The ordinary time-clock does not keep correct and uniform time for the reason that when the spring is wound up it runs at first 10 with the full tension of this spring and runs "fast," while when nearly run down the tension of the spring is so relaxed that the clock runs "slow."

My invention is designed to overcome this 15 objection, and to that end it consists in a peculiar construction and arrangement of the parts of an escapement so combined with the pendulum and an escapement-wheel that the pendulum is not actuated by the escapement-wheel and the power of the mainspring, which 20 is a variable factor, but by an intermediate weight set into action by the escapement-wheel and falling from gravity with a constant force to uniformly actuate the pendulum, as 25 will be hereinafter more fully described with reference to the drawings, in which--

Figure 1 is a front elevation of the escapement. Fig. 2 is a similar view showing a different position of the parts. Fig. 3 is an edge 30 view looking in the direction of the arrow 3 in Fig. 1.

In the drawings, A represents the escapement-wheel of any clock mechanism.

B is the pendulum-bar, connected by two 35 plates *r r* to a suspending-spring *s*, which is supported by a stationary pin *q*. The pendulum-bar is offset at its upper end and is extended above its center of oscillation in the form of an upward extension *n*, having mid-way its length a right-angularly-projecting 40 arm formed by a bar *o* and a subjacent flat spring *p*, which at the front *w* connects the bar *o* with the pendulum extension *n* in an elastic manner.

j and *l* is an elbow-lever arranged on an arbor *t* and turning pivotally at this point. The arm *j* is arranged substantially horizontal and tangential to the top of the escapement-wheel, and *l* projects downwardly to range of engagement with the arm *o p*. *g h* is another elbow-lever, whose arms are arranged at an angle of about forty-five degrees to each other

and are rigidly connected together at *u*, about which point said elbow-lever oscillates. On the outer end of arm *h* is a laterally-projecting pin *k* of a D-shaped cross-section, that engages with the teeth of the escapement-wheel, and on the outer end of arm *g* there is a laterally-projecting pin *f*, that rests on top of an arm *e*. This arm *e* is one of four arms 60 *e d c b*, rigidly connected together and turning about a center *v*. *b* is screw-threaded at its outer end and has an adjustable weight *a* on it, whose gravity in falling actuates the pendulum. *c* is the tappet-arm that strikes 65 the pendulum extension *n* and actuates the pendulum, and *d* is the pallet for the teeth of the escapement-wheel.

In operation the action of the escapement is as follows: When the pendulum is started 70 in the direction of the dotted arrows, Fig. 1, the thin spring *p* under arm *o* presses against arm *l* and releases arm *j* from pallet *d*, letting pallet *d* drop from influence of weight *a* against escape-tooth 1. At the same time arm 75 *c* strikes pendulum extension *n*, giving impulse to the pendulum in the same direction of dotted arrows. Also in the same movement arm *e* presses against pin *f* and lifts arm *h*, with stop-pin *k*, from escape-tooth 2, 80 letting the wheel move in the direction of the full-lined arrow one tooth. In this movement tooth 1 forces pallet *d* back in position to be caught by arm *j*, again raising weight *a* and holding it ready to be released again with the 85 next swing of the pendulum.

i is a piece of metal fastened to the plate of the clock between arms *h* and *j* to keep said arms *h* and *j* in proper position.

m is a flat spring pressing against a flattened surface on the arbor *t* to force arms *l* and *j* into proper position.

In Fig. 2 the pendulum has received its impulse from tappet-arm *c* and tooth 2 has been released from pin *k* and is resting against 95 pallet *d* ready to carry it back in locked position behind arm *j*, after which arm *h*, with pin *k*, falls into position to receive and hold tooth 3 until released by the next motion of the pendulum. The projection *x* of the pallet acts as a stop, striking pin *k* on arm *h*. 100

As thus described, it will be seen that the power to actuate the pendulum is simply the constant and unchanging gravity of weight

a, and the effect of this may be increased or diminished to adjust the strength of the main-spring of the clock by simply screwing the weight *a* along the threaded stem *b* to vary its leverage.

The invention may be applied to any kind of a clock with very little alteration and will enable all clocks at very little cost to keep correct time, like the more expensive regulators for clocks.

Having thus described my invention, what I claim as new, and desire to secure by Letters Patent, is—

1. A clock-escapement, comprising a toothed escapement-wheel, an oscillating pendulum, an oscillating weight, and stop and trip mechanism for the escapement-wheel connecting these three elements as described, whereby only the oscillating weight is made to swing the pendulum, and the pendulum is arranged to trip the stop mechanism as and for the purpose set forth.

2. A clock-escapement, comprising a toothed escapement-wheel, an oscillating pendulum, a four-armed oscillating piece, one arm of which carries a weight, another arm of which applies the force of the fall of said weight to actuate the pendulum, a third arm being fashioned as a pallet to be vibrated by the escapement-wheel, and the fourth arm acting

as a tripping device, an elbow-lever having one arm operated upon by said fourth arm of the four-armed piece, and the other arm provided with a stop for the escapement-wheel, and a second elbow-lever, one arm of which is operated upon by the pendulum, and the other arm of which locks the pallet substantially as and for the purpose described.

3. A clock-escapement, comprising a toothed escapement-wheel, a pendulum with extension *n* and right-angular spring-arm *o p* above its center of oscillation, the four-armed piece *b c d e*, the arm *b* having an adjustable weight, the arm *d* being in the nature of a pallet, and the arm *c* extending to contact with the pendulum extension *n*, the elbow-lever *g h*, the arm *g* of which is extended to contact with *e*, and the arm *h* having on its end a stop-pin *k* for the teeth of the escapement-wheel, the elbow-lever *l j* and spring *m* for holding it in position, the arm *j* acting to lock the pallet, and the arm *l* extending to co-operation with the spring-arm *o p*, and the stationary stop-piece *i* substantially as and for the purpose described.

CARL T. E. ZIMMERMAN.
